United States Patent [19]

Gamm

[11] Patent Number: Des. 281,737

[45] Date of Patent: ** Dec. 17, 1985

[54] POCKETED SHOE

[75] Inventor: Robert J. Gamm, St. Louis Coun., Mo.

[73] Assignee: Kangaroos U.S.A., Inc., St. Louis, Mo.

[**] Term: 14 Years

[21] Appl. No.: 520,696

[22] Filed: Aug. 5, 1983

Related U.S. Application Data

[63] Continuation-in-part of Ser. No. 501,657, Jun. 6, 1983.

[57] CLAIM

The ornamental design for the pocketed shoe, as shown and described.

DESCRIPTION

FIG. 1 is a top plan view of a pocketed shoe showing my new design;

FIG. 2 is a bottom plan view thereof;

FIG. 3 is a rear elevational view thereof;

FIG. 4 is a front elevational view thereof;

FIG. 5 is a left side elevational view thereof;

FIG. 6 is a top-right perspective view thereof;

FIG. 7 is a left side elevational view of a second embodiment of my new design of FIGS. 1-6, all other views thereof being substantially similar to FIGS. 1-4 and 6;

FIG. 8 is a left side elevational view of a third embodiment of my new design of FIGS. 1-6, all other views being substantially similar to FIGS. 1-4 and 6.
